UNITED STATES PATENT OFFICE.

WILLARD THOMAS SEARS, OF PHILADELPHIA, PENNSYLVANIA, ASSIGNOR
TO NILES-BEMENT-POND COMPANY, OF JERSEY CITY, NEW JERSEY.

SPEEDER.

No. 837,969.

Specification of Letters Patent.

Patented Dec. 11, 1906.

Application filed April 16, 1906. Serial No. 311,855.

To all whom it may concern:

Be it known that I, WILLARD THOMAS SEARS, a citizen of the United States, residing in Philadelphia, Philadelphia county, Pennsylvania, have invented certain new and useful Improvements in Speeders, of which the following is a specification.

This invention will be readily understood from the following description, taken in connection with the accompanying drawings, in which—

Figure 1 is a front elevation of a speeder exemplifying my invention, a portion of the front wall being broken away to expose interior mechanism; Fig. 2, an end elevation of the same; Fig. 3, a plan of the same with the cover of the casing removed; Fig. 4, a vertical transverse section of the apparatus; Fig. 5, a plan of the gear-shifter, a portion of its lever appearing in horizontal section; and Fig. 6, a diagrammatic plan of the apparatus.

In the drawings, 1 indicates the driving-shaft; 2, the driven shaft; 3, 4, 5, and 6, dissimilar-sized gears fast on the driven shaft; 7, a pinion splined on the driving-shaft and engageable with gear 3; 8, a gear fast with this pinion and engageable with gear 4; gears 7 and 8 sliding together upon the driving-shaft; 9, a gear splined on the driving-shaft and engageable with gear 5; 10, a gear fast with gear 9 and engageable with gear 6; gears 9 and 10 sliding together as a pair; 11, a spring-detent in the driving-shaft to yieldingly hold the pair of gears 7 and 8 in idle position out of engagement with the mating gears 3 and 4, the pair of gears 9 and 10 having a similar detent; 12, a clutch-pulley loose on the driving-shaft, this clutch-pulley being of most any ordinary or suitable type; 13, the sliding member on the driving-shaft for actuating the clutching mechanism; the illustrated construction assuming that this part slides toward the pulley in order to effect the clutching and from the pulley to effect the release of the clutch; 14, a splined rock-shaft disposed parallel with the other shafts; 15, a cam fast on this rock-shaft; 16, a lever connecting this cam with sliding member 13 of the clutch in such manner that a given angular motion of the rock-shaft will bring about the clutching or unclutching of the driving-pulley; 17, a gear splined upon the rock-shaft and having a pair of arms adapted to straddle either gear 8 or gear 10; 18, a hand-lever united to

the gear-shifter by a pivot at right angles to the axis of the rock-shaft, so that while the shifter and the lever must rock as a unit upon the axis of the rock-shaft the hand-lever is capable of angular motion in a plane parallel with the rock-shaft; 19, a spring carried by the gear-shifter and engaging the lever and serving to hold it in normal position, while permitting it to be flexed in either direction from that position; 20, a fence fixed parallel with the rock-shaft and in position to have an arm of the gear-shifter engage in front of it, the fence preventing the rearward movement of the shifter; 21, a notch or gate in the fence in position to permit the gear-shifter to pass to the rear of the fence when the shifter is in such longitudinal position as to engage double gear 7 8 when the latter is in idle position; 22, a second gate in the fence, similarly related to double gear 9 10; 23, an escutcheon-plate fixed at the front of the apparatus, hand-lever 18 projecting outwardly through slot-work in this plate; 24, a horizontal slot in the plate along in which the shifter-handle may travel while moving from one pair of sliding gears to the other; 25, a vertical slot in the plate in which the shifter-lever may move downward when in longitudinal position corresponding with the engagement of gears 7 and 3; 26, a similar slot corresponding with the engagement of gears 3 and 4; 27, a similar slot corresponding with the engagement of gears 9 and 5; 28, a similar slot corresponding with the engagement of gears 10 and 6; 29, the general casing of the apparatus; 30, horizontal slots connecting the previously-mentioned vertical slots in pairs, and 31 vertical slots connecting the ends of slot 24 with mid-portions of slots 30.

Assuming the hand-lever to be in slot 24, under which condition the shifter-arms will be not only free of engagement with any gear, but will be in front of the fence, so that they could not be put into engagement with a gear. When the shifter is in this condition, both pairs of sliding gears are in the neutral disengaged position, and the clutch is disengaged. Now let it be assumed that it is desired to engage gear 7 with gear 3 to get the lowest selective speed of the system. The shifter being already in slot 24 is to be moved to its leftward extremity. This brings the gate-controlled arm of the gear-shifter opposite gate 21 in the fence and

brings the hand-lever to slot 31. The hand-lever may now be depressed through leftward slot 31, the result being that the arms of the gear-shifter engage gear 8. During this rocking motion of the shifter cam 15 has been oscillated, but through a concentric portion only, therefore not affecting the clutch. The hand-lever is now to be shifted to the leftward extremity of the left slot 30, which results in sliding the gear 7 into engagement with gear 3. The handle may now be depressed in slot 25, the result being the further rocking of the cam and the engagement of the clutch, whereupon the driving-shaft takes on rotation which becomes transmitted to the driven shaft at speed according to the proportion of the selected gears.

The action of the device is similar when adjusting for any other selected speed, and the reverse of the described operation brings about the disengagement of the clutch, the disengagement of any and all gearing, and the disposition of the shifter-arms in front of the fence.

The exemplification illustrates the shifter arranged for engagement with two selective gears and those gears arranged and provided for bringing about four selective speeds; but it is manifest that the system is capable of almost unlimited extension.

Spring-detents 11 serve in retaining the sliding gears in neutral idle position, so that the gear-shifter will find them when it passes through the gates in the fence. It is to be observed that engagement and disengagement of gears can be effected only when the clutch is disengaged and the driving shaft at rest. It might well happen that when an attempt is made to slide a gear into engagement with its mate the angular conditions are such that the teeth abut instead of entering. In such case the hand-lever instead of being positively arrested by the abutting teeth may swing forward against the resistance of spring 19, the gear-shifter being thus put under elastic forwardly-moving strain. Then by a slight turning of either of the gear-shafts the teeth to engage may be brought into proper relationship and the spring will cause them to snap into engagement, or, if desired, the hand-lever may be flexed ahead far enough to come to a vertical slot, permitting it to be rocked so as to throw the clutch into engagement and start up the driving-shaft, whereupon the spring will cause the gear to instantly slide into engagement with its mate. The difficulty of always getting prompt and proper engagement of sliding toothed members, such as gears and toothed clutches, has long been recognized, together with the resulting evils of loss of time in securing any satisfactory engagement at all and the breakage and wearing of the tooth-corners. In my construction I introduce a spring between the

part to be shifted and the operator's hand, which applies the power to accomplish the shifting. At the same time ample provision is made for safeguarding the structure.

I claim—

1. A speeder comprising a shaft, a toothed member splined thereon, a rocking and sliding shifter having an arm to engage said toothed member, a clutch upon said shaft, and mechanism connecting the shifter and clutch, combined substantially as set forth. 70

2. A speeder comprising a shaft, a toothed member splined thereon, a sliding shifter engageable with and disengageable from said toothed member, and a spring-detent engaging the shaft and toothed member and adapted to retain the latter in a given position when the shifter is disengaged from it, combined substantially as set forth. 80

3. A speeder comprising a shaft, a clutch 85 on said shaft, a toothed member splined on the shaft, a rock-shaft parallel with said shaft, a cam on said rock-shaft, mechanism connecting said cam and rock-shaft, and a shifter mounted to slide on and rock with 90 said rock-shaft and having an arm to engage said toothed member, combined substantially as set forth.

4. A speeder comprising a shaft, a toothed member splined thereon, a rocking and sliding shifter having an arm engageable with and disengageable from said toothed member, and a fence disposed in the path of rocking motion of said arm and serving to prevent the disengagement of the arm from the toothed member and having a gate to permit the passage of the arm, combined substantially as set forth. 95

5. A speeder comprising a shaft, a plurality of toothed members independently 105 splined thereon, a rock-shaft, and a shifter mounted to rock with and slide on said rock-shaft and having an arm adapted to be engaged with and disengaged from said toothed members selectively, combined substantially 110 as set forth.

6. A speeder comprising a shaft, a toothed member splined thereon, a rocking and sliding shifter having an arm to engage said toothed member, a clutch upon said shaft, a 115 plate having slots through which a portion of the shifter projects, said slots being so arranged relative to each other that when the shifter may slide it is prevented from rocking, and when rocking it is prevented from sliding, and mechanism connecting the shifter and clutch, combined substantially as set forth. 120

7. A speeder comprising a shaft, a plurality of toothed members splined thereon, a rocking and sliding shifter having an arm 125 to engage said toothed members, a clutch upon said shaft, a plate having slots through which a portion of the shifter projects, said slots being so arranged relative to each other that when the shifter may slide it is pre- 130

vented from rocking and when rocking it is prevented from sliding, and mechanism connecting the shifter and clutch, combined substantially as set forth.

5. 8. A speeder comprising a shaft, a toothed member splined thereon, a sliding shifter having an arm engaging said toothed member, a hand-lever attached to and movable relative to said shifter, and a spring interposed between said hand-lever and shifter and serving to permit the hand-lever to yieldingly advance when the sliding motion of the shifter is arrested, combined substantially as set forth.

15. 9. A speeder comprising a shaft, a toothed member splined thereon, a clutch on the shaft, a rock-shaft, connections between the rock-shaft and the clutch whereby the rocking of the shaft engages and disengages the clutch, a shifter sliding on and rocking with said rock-shaft and engageable with said toothed member, a hand-lever connected with said shifter, and a plate having slots controlling the sliding and rocking motion of the hand-lever, combined substantially as set forth.

10. 10. A speeder comprising a shaft, a clutch thereon, a toothed member splined on the shaft, a rock-shaft, mechanism connecting the rock-shaft and clutch whereby its rocking engages and disengages the clutch, a shifter splined on and rocking with said shaft, a hand-lever pivoted to the shifter, a spring interposed between the lever and shifter to permit the lever to yieldingly advance when the advancing motion of the shifter is arrested, and a plate engaged by the hand-lever and controlling its rocking and sliding motions, combined substantially as set forth.

40. 11. A speeder comprising a shaft, a clutch thereon, a plurality of toothed members splined on the shaft, a rock-shaft, mechanism connecting the rock-shaft and clutch whereby its rocking engages and disengages the clutch, a shifter splined on and rocking with said shaft and engageable with and disengageable from said toothed member selectively, a hand-lever pivoted to the shifter, a

spring interposed between the lever and shifter to permit the lever to yieldingly advance when the advancing motion of the shifter is arrested, and a plate engaged by the hand-lever and controlling its rocking and sliding motions, combined substantially as

55

12. A speeder comprising a shaft, a clutch thereon, a plurality of toothed members splined on the shaft, a rock-shaft, mechanism connecting the rock-shaft and clutch whereby its rocking engages and disengages the clutch, a shifter splined on and rocking with said shaft and engageable with and disengageable from said toothed members selectively, a hand-lever pivoted to the shifter, a spring interposed between the lever and shifter to permit the lever to yieldingly advance when the advancing motion of the shifter is arrested, a plate engaged by the hand-lever and controlling its rocking and sliding motions, and detents engaging the first-mentioned shaft and the gears splined thereon and serving to retain said gears in given position when the shifter is disengaged from them, combined substantially as set forth.

75

13. A speeder comprising a shaft, a clutch thereon, a toothed member splined on the shaft, a rocking and sliding shifter for said gear, mechanism intermediate the shifter and clutch whereby the rocking of the shifter engages and disengages the clutch, a handle movably connected with the shifter, a spring interposed between the handle and shifter to permit the handle to yieldingly advance when the sliding motion of the shifter is arrested, and a plate having slots engaged by said handle for controlling its rocking and sliding motions, said slots being so constructed that when the handle may rock it is prevented from sliding and when it may slide it is prevented from rocking, combined substantially as set forth.
